DESIGN FOR AN ADVERTISING DISPLAY
DEVICE FOR ATTACHMENT TO PARKING
METERSHarold R. Siegel and Morris Paull,
Rochester, N. Y.

Application February 13, 1947, Serial No. 136,890

Term of patent 14 years

(Cl. D1—12)

To all whom it may concern:

Be it known that we, Harold R. Siegel and Morris Paull, both citizens of the United States of America and residents of Rochester, in the county of Monroe and State of New York, have invented a new, original, and ornamental Design for An Advertising Display Device for Attachment to Parking Meters, of which the following is a specification, reference being had to the accompanying drawings, forming part thereof.

Fig. 1 is a front elevational view of an advertising display device for attachment to parking meters, showing our new design; and

Fig. 2 is a side elevational view thereof.

The broken lines are shown for illustrative purposes only.

We claim:

The ornamental design for an advertising dis-

play device for attachment to parking meters, substantially as shown and described

HAROLD R. SIEGEL.
MORRIS PAULL.
